Primary Examiner — Gino Colan*Assistant Examiner* — Gregory G Mclemore(74) *Attorney, Agent, or Firm* — Daryl R. Wright; Greg Carr(57) **CLAIM**

The ornamental design for a model vehicle trailer body as shown and described.

DESCRIPTION

FIG. 1 is an upper, left, front perspective view of a model vehicle trailer body showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is an upper plan view thereof;

FIG. 7 is a lower plan view thereof;

FIG. 8 is an upper, right, rear perspective view thereof;

FIG. 9 is a lower, right, rear perspective view thereof; and,

FIG. 10 is a lower, left, front perspective view of the model vehicle trailer body.

In the drawings, the broken lines illustrate portions of the model vehicle trailer body that form no part of the claimed design.
